PROTECTING DEVICE FOR ELECTRIC CIRCUITS

Irvin L. Worsham, North Little Rock, Ark., assignor of one-third to Roy L. Cochran, North Little Rock, and one-third to Azro L. Barber, Little Rock, Ark.

Application June 20, 1949, Serial No. 100,186

1 Claim. (Cl. 200—118)

1

This invention relates to protecting devices for electric circuits and more particularly to a device capable of forming a short-circuiting path around a piece of apparatus which has been subjected to excessive voltage.

While concerned with electric circuits in general, the present invention relates more particularly to circuits for luminous tubes of the neon type which are supplied from a transformer which should be protected from burning out in the event that the secondary becomes open circuited by failure of apparatus in the secondary.

One of the principal objects of the invention is to provide a simple, cheap construction which is capable of functioning in either horizontal, upright or inclined positions and at the same time may be readily replaced with a minimum of trouble and expense.

Another object of the invention is to provide a protective device which is normally non-conducting but when subjected to currents of a predetermined value becomes conducting so as to function in the nature of a protective relay.

Numerous other objects and advantages of the invention will appear from the following description when it is read in connection with the drawings in which:

Figure 1 is a diagrammatic view of an application of the present invention to a luminous tube display sign;

Figure 2 is a longitudinal sectional view of the protective device embodying the present invention;

Figure 3 is a section similar to Fig. 2 showing a modified construction; and

Figure 4 is a longitudinal section of a unitary construction in which the protective device is mounted co-axially with a luminous tube to be protected.

Referring first to Figure 2 of the drawing, reference character 5 designates an insulating tube preferably of glass sealed in at its ends by metal caps 6 and 7. These caps may be constructed to be held in spring clips like an ordinary cartridge fuse or may be provided with wire connections, as indicated in the drawings. Mounted within the tube and contacting the two end caps 6 and 7 respectively are two resilient conducting springs 8 and 9 preferably made of material such as spring brass. Interposed between the free ends of these springs is an insulating member or capsule 10 which may be composed of gelatin or some other material which is an insulating material under normal conditions but which will carbonize and electrically connect

2

ends of springs 8 and 9 when the circuit to be protected carries excessive current. As shown, the free ends of the springs are reduced in cross section so as to insure good contact with the member or capsule 10.

Figure 3 shows a modified form of protective device in which a single conducting spring 11 is mounted within the tube 5 and engages the capsule 10. One of the sealing discs designated 13 for the end of tube 5 forms a terminal, where 10 13 for the end of tube 5 forms a terminal, where as the terminal adjacent the capsule 10 comprises a disc 12 to which the conducting wire is connected. The disc 12 engages the sealing disc 12a, as indicated.

Figure 1 shows one practical application of the invention to a neon sign supplied with current from the transformer T, primary 16 of which is connected to any suitable source and having a secondary 15 which supplies current to the neon tube designated generally by reference character 14. The part 14 may be of any conventional form which usually consists of a glass tube filled with gas which becomes luminous when current is applied to it. The sections 20 of tube are connected by means of sealing joints 17 and, for purposes of adequate protection, different sections of the tubes are shunted by protective devices a, b and c which may correspond to the embodiments of the invention shown in either Figure 2 or Figure 3.

Whenever conditions arise, for instance in the portion of the sign showing the letters "Go" so as to apply voltage to the protective device a in excess of that to which the device is capable of 35 withstanding, the gelatin capsule 10 carbonizes, forming a conducting path between the ends of springs 8 and 9 and thus short circuiting the section of the sign to which it is connected. Under these conditions, the secondary 15 will remain close circuited so as to supply the remainder of the luminous tubes so that the device a is in series with the letters "od" and Eats." The glass tube 5 may carry a paper label which will become charred when the capsule carbonizes 40 so as to give an exterior indication of the failure. The device a may then be replaced to restore operation of the circuit. Were it not for the protective device forming a current carrying means around a portion of the sign, a failure of one part of the sign would cause a failure of 45 all of the sign and possibly a burning out of the transformer. The protective device of this invention simply and effectively overcomes that possibility with a minimum of expense.

55 In the figures so far described, no attempt has

been made to show the actual manner of securing the protective device in circuit with the electric sign and it is to be understood that while a spring clip attaching means will be useful, any other suitable form of construction may be adopted.

Fig. 4 of the drawing shows a construction or arrangement in which the protector 25 is in series with a short piece of luminous or gaseous tube or resistance equivalent to the same which serves to absorb the potential buildup in the secondary winding of the high tension transformer. The terminals or lead wires 20 are connected in parallel with a sign or the lighting proper. In the event any tube connected to secondary 19 breaks or secondary circuit otherwise opens high voltage current follows the path of least resistance which would be through 20 arcing over protector disintegrating capsule 10 in Fig. 2, creating conductive carbon sufficient to feed tube 21 or equivalent resistance with sufficient current to illuminate same; this alleviates the stress in the secondary of the transformer which is of a current limit type. To summarize, luminous tube 21 is in series with protector 25. This arrangement is to be connected in parallel with the secondary terminals leading to luminous tubes or to a neon sign. Tube 21 lights up when the protector 25 is spent, thus relieving the secondary of potential buildup and it stays lighted until repairs are made and the protector is replaced.

The device may embody the structure of either Fig. 2 or Fig. 3, and it will be so designed that upon the occurrence of excessive current flow through the tube 21 the capsule 10 will carbonize while completing a direct circuit between the two spring wires 8 and 9 or between spring wire 11 and conducting plate 12, thus enabling the tube 21 to function in spite of this failure and avoid-

ing the possibility of transformer burnout or dangerous fire hazards.

One of the outstanding advantages of the present construction is its ability to function in either a horizontal or a vertical position. Protective devices of this general type, as proposed heretofore, have been effective only when placed in a horizontal position so that the fusing material actually flows and connects the two end terminals upon solidification. The present invention makes any such precise positioning unnecessary and yet simplifies the construction to a marked degree.

While I have described only a few forms of my invention, it is to be understood that changes and modifications may be made in the details within the scope of the appended claim without departing from the spirit and scope of my invention.

Having thus described my invention, I claim:

20 A cutout for luminous tube circuits comprising a glass tube, a metal terminal at each end of the tube, a pair of coil springs of conductive material extending lengthwise of the tube, one end of each of said springs contacting one of said terminals, and a gelatinous capsule extending lengthwise of the tube and disposed between the other ends of said springs, said capsule upon overvoltage on the tube being adapted to carbonize to form an electric conductor.
